UNITED STATES PATENT OFFICE

HATTIE M. PFALTZGRAFF, OF ATLANTIC CITY, NEW JERSEY, ASSIGNOR TO H. M. P.
SUPPORTER CO., A CORPORATION OF NEW JERSEY

SUPPORTER

Application filed February 12, 1926. Serial No. 87,777.

My invention relates to belts or supporters utilizable for any of the known purposes to which structures of this character have been commonly applied, and for other desired 5 purposes.

In accordance with my invention, the abdominal, or other organs or parts, are assisted in retaining their true anatomical position and relation by utilizing a supporter comprising an inner belt and an outer belt, both arranged to substantially encircle the body of the wearer, and more particularly, in tightening or belt-fastening operation the outer belt is arranged to apply pressure over a substantial area of the body of the wearer, and particularly the abdominal region.

My invention resides in features and details of construction of the belt or supporter hereinafter described and claimed.

For an illustration of some of the various forms my invention may take, reference is to be had to the accompanying drawings, in which:

Fig. 1 is a front elevational view of a supporter embodying my invention.

Fig. 2 is a rear elevational view of the supporter shown in Fig. 1.

Fig. 3 is a horizontal sectional view, partly in plan, the section being taken on the line 30 3—3 in Fig. 1.

Fig. 4 is a side elevational view of the supporter shown in Fig. 1.

Fig. 5 is a rear elevational view of a supporter showing a modification.

Fig. 6 is a front elevational view of a supporter showing a further modification.

Referring to the drawings, B is an inner belt, preferably of elastic or semi-elastic knitted, porous, or equivalent, fabric or silk, 40 silk and cotton, linen, cotton, or other desirable material. Preferably, belt B lies next to the body of the wearer and extends continuously across the abdomen around the sides to the back and terminates in the vertically extending strips a and b, preferably of inelastic cloth or equivalent fabric. A strip c stitched, or otherwise suitably secured to the strip a, is provided with a plurality of gaps d, utilizable as hereinafter described. There is 45 stitched, or otherwise suitably secured to the

strip b upon its inner face the flap e. A sliding strap S, preferably of inelastic webbing, passes through a flattened ring or link f, preferably disposed at or adjacent one hip of the wearer, one end g of said strap extending 55 through one of the aforesaid gaps d and being secured to the edge of flap e nearest strip c at g¹ and also to the free edge of strip b at g², Fig. 3. It is to be noted that this mode of attachment provides a free strap portion 60 g³, anchored, however, at g¹ and g² between which and the outer surface of the flap e is received the base i of a buckle j, preferably of the character described and claimed in my application Serial No. 730,154, filed 65 August 5, 1924. The other end h of said sliding strap extends through another of the gaps d and is mounted spaced from strap g in a manner similar to that just described to position the base of another buckle j¹ on 70 the flap e. A second sliding strap s¹ corresponding generally to the strap just described also passes through a flattened ring or link k, preferably disposed at or adjacent the hip of the wearer opposite from link f 75 and one end l of said strap after passing beneath the strap-gripping member n and snap member o of buckle j is secured to the edge of strip c, Figs. 2 and 3. The other end m of said second sliding strap after passing beneath the strap-gripping member n¹ and snap member o¹ of buckle j¹ is secured to the 80 edge of strip c, in spaced relation to the end l of said second sliding strap.

Belt B also comprises the hip extensions H 85 integral therewith and extending below the hip over the thighs, forming in effect thigh straps integral with the seamless main inner belt B.

An outer belt B¹ preferably of material 90 corresponding to belt B supplements the action of the inner belt and is particularly designed for applying pressure to desired parts or regions of the body. Belt B¹ comprises 95 two identical or substantially identical sections p and q, the latter secured to belt B at its juncture point with strip a and the former at the juncture point of belt B and strip b. Sections p and q extend in opposite directions from the back of the wearer around the 100

sides and in front terminate in the vertically extending strips *r* and *s*, preferably of inelastic cloth or similar fabric.

A panel or reinforcing strip *t*, or other member for applying pressure to a part of the body and which may be of variable size both as to height and width, depending upon the location of the part to which pressure is to be applied, is formed preferably of relatively heavy inelastic cloth or other suitable material. Said panel is preferably symmetrically located between strips *r* and *s* and preferably is adjustably secured to belt *B* by one or more webs *u*, Fig. 3, whereby the panel may be readily placed in the desired region. A plurality of sets of tension bands or laces *v*, preferably of inelastic material, secured in spaced relation to strips *r* and *s*, after passing through eyelets on either edge of panel *t*, converge, respectively, backward toward a common point and are each secured to a buckle *w*, or similar device. A strap *x*, preferably of inelastic material, connects link *h* with the buckle *w* adjacent thereto and a similar strap *y* connects link *f* with the other buckle *w*. Preferably, protective strips *z*, Fig. 3, of relatively heavy inelastic material are disposed beneath the eyeleted portions of strip *t*. With this arrangement, upon tightening laces *v* after panel *t* has been properly positioned, pressure will be applied over a substantial area of the body in the affected region.

Referring to Figs. 3 and 4, a pair of buckles *a*¹, or equivalent fastening members, are secured respectively to tabs *b*¹ carried by the belt *B* at diametrically opposite sides thereof, adjacent the hips of the wearer. Each buckle is connected by a strip *c*¹, preferably of inelastic material, to an elastic or semi-elastic leg strap *d*¹ formed of some relatively soft material. At its other end, each leg strap is suitably connected, as by a plurality of snap fasteners, not shown, to reinforced portions *e*¹ of the belt *B* immediately adjacent and substantially directly below the panel *t*, Fig. 1.

If desired, one or more elastic stays *f*¹ may be embedded in the strips *a*, *b* and *c* and the flap *e*, and also in the panel *t*, Fig. 3.

The appliance herein described should be worn low upon the abdomen next to the skin and preferably should be drawn on over the feet while the wearer is in a recumbent position. After the appliance has been placed low in the groin, the leg straps *d*¹, *d*² are passed around the insides of the legs and fastened respectively to the buckles *a*¹. With the appliance thus in position, the ends *g* and *h* of strap *S* are adjusted toward the left, while the ends *l* and *m* of strap *S*¹ are adjusted in reverse direction, Fig. 2, thereby tightening both the inner belt *B* and the outer belt *B*¹. When so adjusted, the strap-gripping members *n* and *n*¹ of buckles *j* and

*j*¹ are actuated to positively retain said straps in their adjusted positions by moving the extensions of said strap-gripping members into engagement with their respective snap members *o* and *o*¹. Thereafter straps *x* and *y* are drawn tightly through their respective buckles *w* and, as a result, laces *v* are drawn through the eyelets on either side of the panel *t* and the ends of sections *p* and *q* are drawn toward each other. In this manner, the outer belt *B*¹ comprising the sections *p* and *q* is tightened and the panel *t* is forced inwardly toward the body of the wearer to place the requisite pressure on the abdomen.

In performing this operation, it is to be noted that tension is equally applied to ends *g* and *h* of strap *S*, due to the fact that strap *y* is connected thereto by link *f* whereby said strap *y* is readily adjustable with respect to the connected ends of straps *g* and *h*. Such would not be the case if link *f* were fixedly secured to said straps. Ends *l* and *m* of strap *S*¹ on the opposite side of the supporter which are connected to strap *x* by link *h* are manipulated in a similar manner. It is also to be observed that the converging ends *g* and *h* of strap *S* and strap *y* on one side of the supporter and the converging ends *l* and *m* of strap *S*¹ and strap *x* on the other side of the supporter function to supplement the action of the belts *B* and *B*¹ and particularly is this true in the region wherein said straps overlie the back of the wearer.

This structure allows great freedom of movement of the body, nevertheless applying pressure thereto, and particularly the abdomen or any organ or part to which it is desired particularly to apply pressure.

The leg straps *d*¹ when secured in position, as aforesaid, do not interfere with the freedom of movement of the legs with respect to the body and restrain the supporter from moving upwardly into an improper position.

The integral extensions *H* upon the inner belt *B* closely embrace the thighs and assist in frictionally holding the entire structure in operative position upon the body.

Referring to Fig. 5, there is illustrated a modified form of construction for adjustably securing the various belt sections at the back of the wearer.

As shown therein, one end of belt *B* and the end of section *p* are suitably secured to a strip *a*², or the like. The other end of belt *B* and the end of section *q* are likewise suitably secured to a strip *b*² corresponding generally with strip *a*². If desired, strips *a*² and *b*² may be suitably reinforced, as by securing one or more elastic stays thereto.

Strips *a*² and *b*² may be adjustably secured together in any suitable manner, as by the lace, cord, or the like, *c*² threaded or passing through eyelets *d*² disposed along the outside edges of strips *a*² and *b*². The ends of lace *c*²

may be tied or otherwise adjustably secured together, as indicated at c^2 .

A strap f^2 of suitable non-flexible material stitched as indicated at g^2 , or otherwise suitably secured to the belt structure in any desired region passes preferably through a clip h^2 likewise secured to the belt structure in another region thereof. Primarily, the function of clip h^2 is that of preventing upward movement of strap f^2 . The ends of straps f^2 extend in opposite directions around the body of the wearer exteriorly of the belt structure and are suitably secured to the adjustable panel structure at the front of the wearer, as to the buckles w , Fig. 1. If desired, protective strips i^2 of relatively soft material, as cloth, may be secured to strips a^2 and b^2 so as to extend between the skin of the wearer and the eyelet structure d^2 .

Referring to Fig. 6, there is illustrated a further modification of my invention particularly useful in post-operative cases. At times, in treating such cases it may be desirable to utilize a panel of greater dimensions than that illustrated in Fig. 1 for applying pressure to the abdomen, in which case it may be desirable to utilize the construction illustrated in Fig. 6, wherein a^3 designates a panel of greater dimensions and preferably substantially longer than is the panel t , Fig. 1, said panel a^3 comprising a series of eyelets b^3 , or the like, disposed along opposite outside edges thereof.

Strips c^3 and d^3 secured respectively to the ends of belt sections p and q have secured thereto in spaced relation the tension bands or laces e^3 passing through the eyelets b^3 aforesaid in panel a^3 . One group of such laces, as those secured to the upper part of strip c^3 , converges toward a common point and the laces are secured to a buckle f^3 , or the like, while the lower group is similarly connected to a buckle g^3 . The laces secured to strip d^3 are likewise segregated into two groups and secured, respectively, to buckles h^3 and i^3 .

Straps k^3 and l^3 , respectively, which may be the terminals of straps l and m , Fig. 2, are secured, respectively, to buckles f^3 and g^3 . Similarly, straps m^3 and n^3 , respectively, which may be the terminals of straps g and h , Fig. 2, are secured, respectively, to buckles h^3 and i^3 .

Obviously, when straps k^3 , l^3 , m^3 and n^3 are drawn through their respective buckles, laces e^3 are drawn through the eyelets on either side of panel a^3 to draw strips c^3 and d^3 towards each other. In this manner said panel a^3 is forced inwardly toward the body of the wearer. Moreover, due to the construction described above, pressure is applied over a greater area of the abdomen and more evenly than will ordinarily be the case when a panel of large area is used in the construction of Fig. 1.

What I claim is:

1. A supporter comprising a supporting belt-like structure adapted to extend across the abdomen and around the body, a belt secured to the rear of said structure and divided at the front thereof, a body reinforcement of substantial area at the front of said structure adjustably secured to at least one free end of said belt, and means overlying said belt-like structure and belt for adjusting said body reinforcement with respect to said one free end of said belt.

2. A supporter comprising a supporting belt-like structure adapted to extend across the abdomen and around the body, a belt secured to the rear of said structure and divided at the front thereof, a body reinforcing panel of substantial area at the front of said structure adjustably secured to one end of said belt, means comprising a plurality of laces for drawing the other end of said belt toward the adjacent edge of said panel, and a strap overlying said belt-like structure and belt and connected to said laces.

3. The combination with a belt adapted to encircle the body of the wearer except in a region overlying the abdomen, of a reinforcing panel, and means for securing only the opposite edges of said panel to the ends of said belt, said means comprising a plurality of laces secured to one end of said belt and passing through apertures associated with said panel and thence converging in a direction extending from said panel.

4. The combination with a belt adapted to encircle the body of the wearer except in a region overlying the abdomen, of a reinforcing panel, and means for securing only the opposite edges of said panel to the ends of said belt, said means comprising a fastening device overlying said belt and a plurality of laces diverging from said fastening device in a direction extending toward said panel and passing through apertures associated therewith and thence to one end of said belt.

5. The combination with a belt adapted to encircle the body of the wearer except in a region overlying the abdomen, of a reinforcing panel, and means for securing only the opposite edges of said panel to the ends of said belt, said means comprising a fastening device including a strap overlying said belt and a plurality of laces diverging from said fastening device in a direction extending toward said panel and passing through apertures associated therewith and thence to one end of said belt.

6. A supporter comprising an inner belt adapted to extend across the abdomen and around the body, an outer belt attached to the rear of said inner belt and divided at the front thereof, a body reinforcing panel of substantial area secured to one free end of said outer belt, a plurality of laces secured in spaced relation to the other free end of said outer

belt and passing through spaced openings in the adjacent edge of said panel, and means for securing the free ends of said laces in adjusted position.

5 7. A supporter comprising a supporting belt-like structure adapted to extend across the abdomen, around the body, and to open at the back of the wearer, a belt open at the back of the wearer overlying said belt-like structure, a reinforcing panel biased by said belt toward the abdomen of the wearer, and means for tightening said belt-like structure and belt comprising structure secured to said belt at the front of the wearer, slidably engaging said reinforcing panel, and secured to said belt-like structure at the back of the wearer.

10 8. A supporter comprising a supporting belt-like structure adapted to extend across the abdomen, around the body, and to open at the back of the wearer, a belt open at the back of the wearer overlying said belt-like structure and having its ends secured to the corresponding ends of said belt-like structure, a reinforcing panel biased by said belt toward the abdomen of the wearer, and means for simultaneously tightening said belt-like structure and belt at one position comprising means for individually tightening said belt at another position.

15 9. A supporter comprising a supporting belt-like structure adapted to extend across the abdomen, around the body, and to open at the back of the wearer, a belt comprising a plurality of sections overlying said belt-like structure, two of said sections at their ends facing each other being secured to the respective ends of said belt-like structure, a reinforcing panel secured to the other ends of said last-named sections, and means for simultaneously tightening said belt-like structure and belt at their common end portions comprising means for individually tightening said belt at said reinforcing panel.

20 10. A supporter comprising a supporting belt-like structure adapted to extend across the abdomen, around the body, and to open at the back of the wearer, a belt comprising a plurality of sections overlying said belt-like structure, two of said sections at their ends facing each other being secured to the respective ends of said belt-like structure, a reinforcing panel adjustably secured to the other ends of said last-named sections, and means for simultaneously tensioning said belt-like structure and belt and for moving an edge of said panel toward the end of one of said last-named sections.

25 11. A supporter comprising a supporting belt-like structure adapted to extend across the abdomen, around the body, and to open at the back of the wearer, a belt comprising a plurality of sections overlying said belt-like structure, two of said sections at their ends facing each other being secured to the respec-

tive ends of said belt-like structure, a reinforcing panel adjustably secured to the other ends of said last-named sections, and means comprising a strap for simultaneously tensioning said belt-like structure and belt and for moving an edge of said panel toward the end of one of said last-named sections.

70 12. A supporter comprising an inner belt adapted to extend across the abdomen around the body and terminating in substantially non-yielding strips at the back of the wearer, an outer belt comprising a pair of substantially duplicate sections, each non-adjustably attached to said inner belt in the region of said strips, means comprising a pair of single straps lying adjacent but outside of said belts and extending toward the front of the wearer for adjustably closing said belts, a panel of substantial area in a region substantially diametrically opposite from said strips secured to the free end of one of said duplicate sections, and means connected to one of said single straps for drawing the free end of another of said sections toward the adjacent edge of said panel.

75 13. A supporter comprising an inner belt extending across the abdomen around the body and terminating in substantially non-yielding strips at the back of the wearer, an outer belt comprising a pair of substantially duplicate sections, each attached to said main belt in the region of said strips, means comprising a pair of single straps lying adjacent but outside of said belts and extending toward the front of the wearer for adjustably closing the inner and outer belt at the back of the wearer, a panel of substantial area in a region substantially diametrically opposite from said strips secured to the free end of one of said duplicate sections, and means connected to one of said single straps and operative in a plurality of vertically spaced regions for drawing the free end of another of said sections toward the adjacent edge of said panel.

80 14. A supporter comprising an inner belt extending across the abdomen around the body and terminating in substantially non-yielding strips at the back of the wearer, an outer belt comprising a pair of substantially duplicate sections, each attached to said main belt in the region of said strips, means comprising a pair of single straps lying adjacent but outside of said belts and extending toward the front of the wearer for adjustably closing the inner and outer belt at the back of the wearer, a panel of substantial area in a region substantially diametrically opposite from said strips secured to the free end of one of said duplicate sections, a plurality of laces secured in spaced relation to the free end of another of said sections passing through spaced openings in the adjacent edge of said panel, and means for adjustably se-

curing the free ends of said laces to one of said single straps.

15. A supporter comprising an inner belt extending across the abdomen around the body and terminating in substantially non-yielding strips at the back of the wearer, an outer belt comprising a pair of substantially duplicate sections, each attached to said main belt in the region of said strips, a strap having its ends secured in spaced relation to one of said strips, a second strap having its ends secured in spaced relation to another of said strips, said straps lying adjacent but outside of said belts and extending in opposite directions from the back toward the sides of the wearer, whereby tightening of the belts is effected upon movement of said straps in the respective directions in which they extend, a link freely slidable upon each of said straps, single straps secured respectively to each link and extending toward the front of the wearer, a panel of substantial area in a region substantially diametrically opposite from said strips secured to the free end of one of said duplicate sections, a plurality of laces secured in spaced relation to the free end of another of said duplicate sections, said laces passing through spaced openings in the adjacent edge of said panel, and a buckle secured to the free ends of said laces receiving one of said single straps.

16. A supporter comprising a supporting belt-like structure adapted substantially to encircle the body of the wearer, a belt comprising two sections secured to respective ends of and overlying said belt-like structure, and of such length that the free ends of said sections terminate short of each other, a reinforcing panel disposed therebetween, and tightening means comprising a pair of strap structures each secured to the free end of one of said sections, slidably engaging said reinforcing panel, overlying the said one of said sections, and secured to said belt-like structure at the opposite end thereof to which said other section is secured.

17. A supporter comprising a supporting belt-like structure adapted substantially to encircle the body of the wearer, a belt comprising two sections secured to respective ends of and overlying the belt-like structure, and of such length that the free ends of said sections terminate short of each other, a reinforcing panel disposed therebetween, a pair of strap structures each secured to the free ends of one of said sections, slidably engaging said reinforcing panel, reversely extending over said section, and secured to said belt-like structure at the opposite end thereof to which said other section is secured, and means to adjust the effective length of said strap structures simultaneously to effect tightening of said belt-like structure and said belt.

18. A supporter comprising an inner belt adapted to extend across the abdomen and

around the body, outer belt structure fixedly attached to said inner belt and having free ends at the front thereof, a body reinforcing panel, a loop of adjustable length having one end fixedly secured to and extending from a free end of said outer belt structure, slidably engaging the adjacent edge of said panel, and reversely extending to a point of attachment to the supporter proper, and means similarly connecting the other free end of said belt structure to the other, adjacent side of said panel.

19. A supporter comprising an inner belt structure adapted to extend across the abdomen, around the body, and to open at the back of the wearer, an outer belt structure comprising sections overlying said inner belt structure and fixedly secured to corresponding edges thereof, a reinforcing panel biased by said outer belt structure toward the abdomen of the wearer, and means for tightening said supporter comprising means for simultaneously tightening the outer and inner belt structures concurrently with individual tightening of said outer belt structure.
